UNITED STATES PATENT OFFICE

100,301

DESIGN FOR AN ORGAN CONSOLE

George H. Stephens, Northbrook, Ill., assignor to The Hammond Clock Company, Chicago, Ill.,
a corporation of Delaware

Application May 1, 1936, Serial No. 62,401

Term of patent 14 years

To all whom it may concern:

Be it known that I, George H. Stephens, a citizen of the United States, residing at Northbrook, in the county of Cook and State of Illinois, have invented a new, original, and ornamental Design for an Organ Console, of which the following is a specification, reference being had to the accompanying drawing, forming part thereof,

The figure is a perspective view of the organ console, showing my design.

I claim:

The ornamental design for an organ console as shown.

In witness whereof, I hereunto subscribe my name this 27th of day of April, 1936.

GEORGE H. STEPHENS,
